INSULATED JUMPER CLIP

Daniel C. Heck, Deerfield, Ill., assignor to
Illinois Tool Works Inc., Chicago, Ill.

Filed Sept. 23, 1970, Ser. No. 25,166

Term of patent 14 years

Int. Cl. D13—99
U.S. Cl. D26—1

Fig. 1

Fig. 2

Fig. 3

Fig. 4

Fig. 5

FIG. 1 is a front elevational view of an insulated jumper clip.

FIG. 2 is a top view of the clip shown in FIG. 1.

FIG. 3 is a bottom view of the clip shown in FIG. 1.

FIG. 4 is a sectional view taken along line 4—4 of FIG. 1; and

FIG. 5 is a sectional view taken along line 5—5 of FIG. 1.

I claim:

The ornamental design for an insulated jumper clip, as shown.
